CLAIM

The ornamental design for a foldable chair, as shown and described.

DESCRIPTION

FIG. 1 is a perspective view from the front, top and left side of a foldable chair showing my design;

FIG. 2 is a front view thereof;

FIG. 3 is a rear view thereof;

FIG. 4 is a left side elevational view thereof;

FIG. 5 is a right side elevational view thereof;

FIG. 6 is a top plan view thereof; and,

FIG. 7 is a bottom plan view thereof.

The fragmented cross-hatch pattern shown on the side straps in FIGS. 1, 2 and 6 is understood to be continuous throughout.

The broken lines shown on the seat and backrest represent stitching.

FIGS. 2 through 7 have been shown on a reduced scale.
